OUTER SPACE VEHICLE TOY

John W. Ryan, Los Angeles, and Gerald W. Schmidt, Tarzana, Calif., assignors to Mattel, Inc., a corporation of California

Filed Jan. 19, 1967, Ser. No. 5,483

Term of patent 14 years

(Cl. D34—15)

Fig. 1

Fig. 2

Fig. 3

Fig. 4

Fig. 5

Fig. 6

FIGURE 1 is a side elevational view of an outer space vehicle toy showing our new design;

FIGURE 2 is a top plan view thereof;

FIGURE 3 is a side elevational view of the side opposite FIGURE 1;

FIGURE 4 is a bottom plan view of FIGURE 3;

FIGURE 5 is an end elevational view taken from the right of FIGURE 1; and

FIGURE 6 is an end elevational view taken from the left of FIGURE 1.

We claim:

The ornamental design for an outer space vehicle toy, as shown.
